(57) **CLAIM**

The ornamental design for a multiple outlet valve for measured gauged flow, as shown and described.

DESCRIPTION

FIG. 1 is an upper perspective view of the valve.

FIG. 2 is a front view of the valve.

FIG. 3 is a rear view of the valve.

FIG. 4 is a right end view of the valve.

FIG. 5 is a left end view of the valve.

FIG. 6 is a top view of the valve; and,

FIG. 7 is a bottom view of the valve.
